ATTORNEYS.

UNITED STATES PATENT OFFICE.

WILLIAM FRANKLIN MATHUES, OF SWARTHMORE, PENNSYLVANIA.

DESIGN FOR A SERVICE AND MEMORIAL TABLET.

54,107.

Specification for Design.

Patented Nov. 4, 1919.

Application filed February 28, 1919. Serial No. 279,895. Term of patent 3½ years.

To all whom it may concern:

Be it known that I, WILLIAM FRANKLIN MATHUES, a citizen of the United States, residing at Swarthmore, in the county of Delaware, State of Pennsylvania, have invented a new, original, and ornamental Design for Service and Memorial Tablets, of which the following is a specification, reference being had to the accompanying drawing, forming part thereof.

The figure is a face view of a service and memorial tablet, showing my new design.

I claim:—

The ornamental design for a service and memorial tablet, as shown.

WILLIAM FRANKLIN MATHUES.
